OTTO ANDERS, OF BERLIN-SCHMARGENDORF, GERMANY, ASSIGNOR TO SIEMENS & HALSKE AKTIENGESELLSCHAFT, OF WERNERWERK, SIEMENSSTADT BEI BERLIN, GERMANY

TELEPHONE SYSTEM

Application filed February 27, 1928, Serial No. 257,202, and in Germany August 15, 1927. Renewed April 7, 1930.

The invention relates to an arrangement in telephone systems wherein several subscribers are allotted to one line as is the case in rural party lines, for example. The invention aims at facilitating the traffic between the subscribers connected to a party line without influencing the connecting devices in the exchange and at permitting establishment of connections to the exchange on the part of a subscriber on the party line. This is achieved in a particularly simple manner by the ringing of the exchange on the part of a telephone station on the party line only taking place when the ringing operation is of a particular duration.

The connection of the party line to the exchange is preferably effected indirectly through a repeater. This repeater is so formed that the bridge at the side of the party line is normally open in order to prevent disturbing influences during mutual calls of the subscribers on the party line, due to damping. The selection of a subscriber, not associated with the party line, e. g., a subscriber in the main exchange, is accomplished by the calling party line in such a manner as to actuate a time switching device which closes the bridge in the repeater. The mutual calling of the subscribers is brought about in the usual manner by Morse signals in the magneto.

The drawing shows by way of example a rural party line R. P. L. connected to an automatic telephone exchange M. E. over the usual lineswitch L. S. of which only the wipers 13, 14 and 15 are shown. In accordance with a common practice of schematic representation, the contacts operated by relays have been shown in the circuit separated from their relays and placed conveniently with relation to apparatus in which they perform some function. The relays are designated by capitalized reference characters, while their contacts are designated by corresponding small characters and numerals. An ordinary relay is represented by zig zag lines with a heavy line therethrough; a slow acting relay is shown in a rectangular cage; and a non-inductive resistance is indicated by ordinary zig zag lines. The mode

of operation will now be described in detail.

If the party line subscriber PLS of the rural party line R. P. L. wishes to enter into communication with a subscriber of the automatic main exchange ME he must actuate his magneto 3 longer than usual; consequently, the A. C. relay A is energized over the magneto 3, switchhook 1, conductors 10 and 11 and condenser 22. The energization of the thermo-electric relay Th is accomplished over the contact 1a of relay A, so that now, if relay A has been operated for the proper period of time, the V2 relay responds from ground, th, V2, to battery. Relay V2 operates its contacts 1v2 and 2v2 and connects thereby the impulse relay A1, which energizes over: ground, impulse contact 7, switchhook contact 8, choke coil 6, resistance 5, conductors 10 and 11, contacts 1r and 2r, left hand windings of repeater 12, contacts 1v2 and 2v2, winding of relay A1, to battery. After the retraction of the A. C. relay A, the relay V2 consequently lies in the circuit from ground, 1a1, V2, battery. The sending of impulses commences now, and, upon the first retraction of A1, relay V1 will respond from ground, 4c, 3v2, V1, resistance 20, to battery. The relay V1 having been previously short circuited over the contact 2a1. Thus, the line conductors 16 and 17 are connected interrupted to ground over 1v1, 2v1 and 3a1.

The lineswitch LS was operated in the usual manner immediately upon the energization of impulse relay A1, and consequent closure of its contacts 3a1, and rotated its wipers 13, 14 and 15 into engagement with the trunk conductors 16, 17 and 18. The impulses transmitted by the calling station PLS by means of a well known calling device, of which only the impulse contact 7 is shown, effects a selector switch in the main exchange in a manner familiar to anyone versed in telephony. No detail account of this operation is therefore given in this application.

After the termination of the usual selector setting, the relay V1 will retract so that a speaking connection between the subscriber of the rural party line and a subscriber of the

automatic exchange is established. The release will take place in known manner.

If a connection is to be established in reverse direction, then the rural party line is reached over a selector in the main exchange seizing the trunk line comprising conductors 19', 20' and 21'. In this case, by energizing the C relay, the lineswitch of the party line is blocked and at the same time the energization of the relay U occurs from ground, 1c, 1v, U, to battery. Due to the closure of contact 1u, the relay V is energized over 2c, 3r, 1u, V, to battery, so that afterwards the relay RII responds from ground 3c, 3v, RII resistance 21, to battery. Since the relays RII and U are operated, no automatic ringing occurs (contacts 2u and 3u are opened, contacts 4r and 5r are closed). By energizing the RI winding over the contact 6c and conductors 20' and 21' in the selector, the relay R will retract due to the differential action of the two windings. The relay U also retracts due to the opening of contacts 1v, and the RI winding is intermittently interrupted during the actuation of the dial at the calling main exchange for the purpose of sending out ringing impulses, so that the RII winding comes into action and applies the ringing current to the rural line over the contacts 4r and 5r. At the end of the ringing current impulses, the speaking circuit is closed through contacts 1r, 2r, and 5c. The release of the connection is accomplished in known manner.

If the party line is connected to a manually operated telephone system, the switching on of the line signal after the actuation of the time switching device is accomplished by means of an auxiliary relay.

What is claimed is:

1. In a telephone system, a party line, an automatic exchange, a line provided for extending calls from said party line to said exchange, a time switching device at said exchange, means for transmitting ringing current of particular duration over said call extending line, and means responsive to said ringing current for actuating said time switching device to effect a connection between said party line and said exchange.

2. In a telephone system, a party line, an automatic exchange, a line provided for extending calls from said party line to said exchange, a thermo-electric time switching device at said exchange, means at a calling party line station for transmitting ringing current over said call extending line, means at said exchange responsive to said ringing current, and means actuated thereby for operating said time switching device only if said ringing current is of a particular duration to effect a connection between said party line and said exchange.

3. In a telephone system, a party line, an automatic exchange, a line provided for extending calls from said party line to said ex-

change, an alternating current relay connected to said call extending line, means at a calling party line station to transmit ringing current over said call extending line to operate said alternating current relay, a thermo-electric time switching device, and means actuated by said relay for operating said time switching device to effect a connection between said calling party line and said exchange only if that ringing current is of particular duration.

4. In a telephone system, a party line, an automatic exchange, a line to said exchange for extending calls from a calling party line to a called line in said exchange, a repeater and an automatic switch associated with said call extending line and normally disconnected therefrom, a time switching device in said exchange, means for transmitting ringing current of a particular duration over said call extending line, means responsive to said ringing current for actuating said time switching device, and means operated by said time switching device to connect said repeater to said call extending line and to close a starting circuit for said automatic switch to effect a connection between said calling party line and said called line in the exchange.

5. In a telephone system, a party line, an automatic exchange, a repeater comprising two inductively connected sections, one of said sections being normally open, a line terminating in said open section of said repeater and provided for extending calls from a calling party line to a called line in said exchange, an automatic switch connected to said other section of said repeater, a time switching device, means at a calling party line station for transmitting ringing current over said terminating line, means responsive to said ringing current for actuating said time switching device, and means operated by said time switching device after the lapse of a certain period depending on the continuous application of said ringing current, for closing the normally open section of said repeater and for closing a starting circuit for said automatic switch to effect a connection between said calling party line and said exchange.

6. In a telephone system, a party line, an automatic exchange, a repeater comprising two inductively connected sections, one of said sections being normally open and provided with an impulse receiving and repeating relay, a line terminating in said open section of said repeater and provided for extending calls from a calling party line to a called line in said exchange, an automatic switch connected to said other section of said repeater, a time switching device, means at a calling party line station for transmitting ringing current over said terminating line, means responsive to said ringing current for actuating said time switching device, and

- means operated by said device after the lapse of a certain period depending upon the continuous application of said ringing current, for closing the normally open section of said repeater and for connecting said impulse relay to said terminating line, and for closing a starting circuit for said automatic switch to effect a connection between said calling line and said automatic exchange.
10. 7. In a telephone system, a substation, an automatic exchange, a line for extending calls between the two, means at the substation for transmitting ringing current over said line, and means at the exchange responsive to ringing current of a particular duration over said line for effecting a connection between said substation and said exchange.
8. In a telephone system, an automatic exchange, a line terminating in said exchange, a substation on said line, means at said substation for transmitting ringing current over said line to said exchange, a relay in said exchange operated by said ringing current and maintained operated thereby throughout the duration thereof, and means controlled by said relay and effective after said relay has been maintained operated for a certain period to connect said substation to said exchange.
30. 9. In a control system, one station, another station remotely disposed therefrom, a source of direct current at said one station, an alternating current source at said other station, a line interconnecting said stations, and means in said one station responsive to a flow of alternating current over said line from the current source at the remote station for setting up a direct current flow over said line from the current source at said one station.
40. 10. In a control system, one station, another station remotely disposed therefrom, a source of direct current at said one station, a current source at said other station, a line interconnecting the two stations, apparatus at the said one station, means in said one station responsive to a current flow over said line from said remote station source for setting up a direct current flow over said line from said one station source, and means at said remote station for thereafter controlling the current flow from said one station source to operate said apparatus.
50. 11. In a telephone system, a substation, an automatic exchange, a line extending between the two, automatic switches for extending a call to substation in the exchange, a current source at the substation, a direct current source in the exchange, means in the exchange responsive to a current flow over said line from said substation source for setting up a direct current flow over said line from said exchange source, and means at the substation for thereafter controlling the current flow from said exchange source to operate said automatic switches.
12. In a telephone system, a calling line, a substation on said line, an exchange having automatic apparatus for establishing a telephonic connection between said calling line and a called line, a current source at said substation, a current source in said exchange, means in the exchange responsive to a current flow over said calling line from said substation source for establishing a current flow over said calling line from said exchange source, and means at the substation for producing interruptions in the current flow from said exchange source for controlling said automatic apparatus to establish a connection between said calling line and a called line.
13. In a telephone system, a calling line, a substation on said line, an exchange having automatic apparatus for establishing a telephonic connection between said calling line and a called line, a current source at said substation, a current source in said exchange, timing means in the exchange responsive to a current flow of a particular duration over said calling line from said substation source for establishing a current flow over said calling line from said exchange source, and means at the substation for producing interruptions in the current flow from said exchange source for controlling said automatic apparatus to establish a connection between said calling line and a called line.
14. In a telephone system, a calling line, a substation on said line, a telephone exchange, a source of alternating current at the substation, a source of direct current at the exchange, and means in the exchange responsive to a flow of alternating current over said line for establishing a connection between said substation and said exchange and for setting up a flow of direct current over said line.
15. In a telephone system, a party line, an exchange, means for transmitting ringing current over said line to said exchange, and means in said exchange responsive to the flow of ringing current of a particular duration only for effecting a connection between said line and said exchange.
16. In a telephone system, a line having a substation provided with a source of current, an exchange, and means in said exchange responsive to a flow of current of a particular duration only over said line from said source for effecting a connection between said line and said exchange.
17. In a telephone system, an exchange, a calling line terminating in said exchange, a plurality of substations on said line, each substation having means for generating current to signal other substations on the line, and an automatic switch in said exchange responsive to current of a definite duration only.

from one of said substations for extending the calling line therein.

18. In a telephone system, an exchange, a line terminating in said exchange, a plurality of substations on the line, each substation having a hand generator whereby the other stations on the line can be signalled and an automatic switch in the exchange responsive to the continued operation of any one of said hand generators for a definite minimum period for extending said line therein.

In witness whereof, I hereunto subscribe my name this 26th day of January, A. D. 1928.
